CHUCK FOR COIL WINDING MACHINES

John William Miller, London, England, assignor to Goodmans Industries Limited, Wembley, Middlesex, England, a British company

Application September 7, 1943, Serial No. 501,490
In Great Britain December 31, 1942

9 Claims. (Cl. 242—9)

This invention relates to chucks for coil winding machines and more especially to chucks for use in winding coils on microphone or telephone cone diaphragms.

Whilst the chuck is applicable to coil winding machines generally it is more especially applicable to electrical coil winding machines as described in my co-pending application Serial No. 477,883, filed March 3, 1943.

In the case of cone diaphragms for microphones the position of the coil relatively to the cone is important as the characteristics of the cone depend on the position of the coil.

In the case of multi-layer coils provision must also be made to ensure that the separate layers are correctly superimposed.

It is the object of the present invention to provide a chuck by means of which the coil is correctly positioned relatively to the cone of a microphone diaphragm.

A further object of the invention is to provide a chuck which ensures that the separate layers of a multi-layer coil are correctly positioned and guided on to a cylindrical extension of the cone.

Another object of the invention is to provide means for clamping the diaphragm in position whilst one or more layers of coil are being wound on the cylindrical extension.

Still another object of the invention is to provide a magnetic chuck of which an armature serves to clamp the diaphragm in position in the chuck, the armature at the same time serving to position one end of one or more layers of coil in the correct position relatively to the cone of the diaphragm.

According to the present invention a chuck for an electrical coil winding machine, is provided with a fixed cheek, shaped to conform with the shape of a diaphragm having a conical portion and a cylindrical extension on which latter one or more layers of coil are to be wound, the cylindrical extension being adapted to be engaged by a former which is located between the fixed cheek and a removable cheek and is pressed against the fixed cheek by a nut bearing against the removable cheek and screwing on a screwed spindle secured to the fixed cheek, whilst a guide, for positioning one or more layers of coil to be wound on the cylindrical portion of the diaphragm, is provided for positioning the layer or layers of coil whilst being wound on the cylindrical portion.

The guide is preferably formed of two diametrically separated parts which are held in position magnetically.

The guide may be of such a shape as to con-

form with the shape of the diaphragm and thus serve to clamp the diaphragm against the fixed cheek.

The invention will now be described with reference to the accompanying drawing showing, by way of example, a magnetic chuck for use in winding a coil, formed of one or more layers, on a cylindrical extension of a cone diaphragm for a microphone.

10 In this drawing—

Fig. 1 shows a side elevation of the chuck,
Fig. 2 shows a longitudinal section of the chuck,
Fig. 3 shows a view of a clamping member, and
Fig. 4 shows a view of the left hand end of the
15 chuck, with the clamping member, diaphragm, movable cheek and nut removed.

As shown in the drawing the chuck is provided with a soft iron end plate 1 and an aluminium end plate 2 which are secured to a soft iron tube 3.

The tube 3 is adapted to be secured to a shaft 3a of a coil winding machine.

Between the end plates is located a tubular permanent magnet 4 preferably of a ferrous alloy containing aluminium and nickel, with or without cobalt, for example the alloy known on the market under the name "Alnico."

The end plate 2 is secured to a soft iron plate 5 of which the left hand face is shaped to conform with the shape of the diaphragm 6.

The plates 1, 2, 5 with the magnet 4 between the plates 1, 2 are secured together by screws 7.

Around the plates 1, 2 is secured a casing 8 of soft iron.

35 The assembly so far described is adapted to be secured to the shaft 3a by means of set screws of which one is shown at 9.

In the plate 2 are secured soft iron pins 11 of circular cross section which fit into holes 12 of larger diameter in the plate 5 whereby air gaps are formed.

40 The diaphragm 6 is provided with a cylindrical portion 13, on which one or more layers of coil 14 are to be wound, a conical portion 15 and a flat flange 16 by which it is adapted to be secured in a microphone.

The plate 5 has a conical face 17 and a flat face 18 which conform with the cone 15 and the flange 16 respectively.

45 The plate 5 is also provided with a flat face 19 against which bears a former 20 for receiving the cylindrical portion 13 of the diaphragm 6.

The plate 5, which forms the fixed cheek for the chuck, is also provided with a flange 10 which serves as an abutment for a guide 21 provided

with a peripheral rim 22 which is guided by the cylindrical portion 23 of the plate 5. The face of the guide adjacent the diaphragm 6 conforms with the shape of the conical portion 15 and flange 16 of the diaphragm 6.

As shown in Fig. 3 the guide 21 is formed of two parts 24, 25 which are separated along a diametral line 26 so that they can be slid over and off the diaphragm 6 conveniently.

The guide 21 serves to clamp the diaphragm 6 against a plate 5 as it forms the armature of the magnet 4 by which it is attracted.

The attractive force of the magnet 4 is such that it holds the guide 21 in position whilst the coil 14 is being wound on the cylindrical portion 13 of the diaphragm 6.

The parts 24, 25 are provided with notches 27 in one or other of which the wire of the coil 14 can be nipped so as to hold it firmly whilst the coil 6 is being wound.

The central portion 28 of the guide 21 is located in a plane at right angles to the axis of the cylindrical portion 13 and is made of the necessary thickness to determine the position of the first turn of the coil 14 on the cylindrical portion 13. The guide 21 also serves to position the various layers in the case of a multi-layer coil 14.

The former 20 is clamped in position by a removable cheek 29 of which the face adjacent the former 20 is provided with a recess of two different diameters 30, 31, the larger diameter serving to receive the cylindrical portion 13 and the smaller diameter the former 20.

The removable cheek 29 is preferably milled on its periphery.

The removable cheek 29 is fitted on a screw threaded spindle 32 and is forced against the former 20 by a nut 33 which is preferably milled on its periphery.

For the purpose of mounting a diaphragm 6 in the chuck in order to wind a coil 14 on the cylindrical portion 13 thereof the nut 33, removable cheek 29 and guide 21 are removed from the spindle 32. The removal of the guide 21 is facilitated as its two parts 24, 25 can be slid laterally off the plate 5.

A diaphragm 6, mounted on a former 20, is now passed over the spindle 32, the diaphragm 6 being placed against the plate 5 and the former 20 engaging with the flat surface 19 of the plate 5. The two halves 24, 25 of the guide 21 are now placed in position and as the guide 21 is attracted by the magnet 4, the diaphragm is consequently held in position against the plate 5. The removable cheek 29 and the nut 33 are placed in position on the spindle 32, the nut 33 being tightened to hold the cheek 29 and the former 20 in position on the spindle. The wire of the coil 14 is engaged with one of the notches 27 and the spindle 32 is ready for being driven so as to wind the coil 14 in one or more layers on the cylindrical portion 13 of the diaphragm 6.

I claim:

1. In a chuck for an electrical coil winding machine, the combination with a fixed cheek having a conical portion, of a screw threaded spindle secured to said fixed cheek, a removable cheek mounted on said spindle, a former between said cheeks; a diaphragm having a cylindrical and a conical portion mounted on said former and said first-mentioned conical portion, said cylindrical portion being adapted to have a coil of one or more layers wound thereon, a nut screwed on said spindle, said nut bearing against said removable cheek thus pressing said former against said fixed

cheek, and a guide located around said cylindrical portion adjacent said fixed cheek, said guide serving to determine the position of said coil on said cylindrical portion relatively to said conical portion.

2. In a chuck for an electrical coil winding machine, the combination with a fixed cheek having a conical portion, of a screw threaded spindle secured to said fixed cheek, a removable cheek mounted on said spindle, a former between said cheeks; a diaphragm having a cylindrical and a conical portion mounted on said former and said first-mentioned conical portion, said cylindrical portion being adapted to have a coil of one or more layers wound thereon, a nut screwed on said spindle, said nut bearing against said removable cheek thus pressing said former against said fixed cheek, and a guide located around said cylindrical portion adjacent said fixed cheek, said guide serving to determine the position of said coil on said cylindrical portion relatively to said conical portion, said guide being formed of two diametrically separated parts.

3. In a chuck for an electrical coil winding machine, the combination with a fixed cheek having a conical portion, of a screw threaded spindle secured to said fixed cheek, a removable cheek mounted on said spindle, a former between said cheeks; a diaphragm having a cylindrical and a conical portion mounted on said former and said first-mentioned conical portion, said cylindrical portion being adapted to have a coil of one or more layers wound thereon, a nut screwed on said spindle, said nut bearing against said removable cheek thus pressing said former against said fixed cheek, and a guide located around said cylindrical portion adjacent the fixed cheek, said guide serving to determine the position of said coil on said cylindrical portion relatively to said conical portion, said guide having its face adjacent the diaphragm of a shape conforming with the shape of said diaphragm, said guide serving to clamp said diaphragm against said fixed cheek.

4. In a chuck according to claim 1, said guide being of soft iron and magnetic means holding said guide in position.

5. In a chuck according to claim 1, a flange on said fixed cheek, and a peripheral rim on said guide, said rim being adapted to engage with the periphery of said fixed cheek and to cooperate with said flange for positioning said guide.

6. In a chuck according to claim 1, a permanent magnet system, said magnet system including an aluminium plate located adjacent said fixed cheek, said aluminium plate having a circular row of soft iron pins secured thereto, said fixed cheek being of soft iron and having therein a circular row of holes which are adapted to receive said pins with clearance, a soft iron plate arranged in spaced relation to said aluminium plate, a tubular permanent magnet located between said soft iron plate and said aluminium plate, and means for connecting said soft iron plate and said aluminium plate to said fixed cheek.

7. In a chuck according to claim 1, a permanent magnet system, said magnet system including an aluminium plate located adjacent said fixed cheek, said aluminium plate having a circular row of soft iron pins secured thereto, said fixed cheek being of soft iron and having therein a circular row of holes which are adapted to receive said pins with clearance, a soft iron plate arranged in spaced relation to said aluminium plate, a tubular permanent magnet located between said soft iron plate and said aluminium plate, a tube to oppose

ends of which said aluminium plate and soft iron plate are secured, said tube being adapted to be fitted on and secured to a driving shaft, and means for securing said soft iron plate and said aluminium plate to said fixed cheek.

8. In a chuck according to claim 1, a permanent magnet system, said magnet system including an aluminium plate located adjacent said fixed cheek, said aluminium plate having a circular row of soft iron pins secured thereto, said fixed cheek being of soft iron and having therein a circular row of holes which are adapted to receive said pins with clearance, a soft iron plate arranged in spaced relation to said aluminium plate, a tubular permanent magnet located between said soft iron plate and said aluminium plate, and means for connecting said soft iron plate and said aluminium plate to said fixed cheek, said connecting means including screws passing through the soft iron plate and the aluminium plate and screwing into said fixed cheek, and a casing fitted around and secured to said aluminium plate and said soft iron plate and enclosing said tubular magnet.

9. A chuck for the purpose described comprising a soft iron fixed circular cheek having one face flat and its other face flat but with a central conical portion of which the apex is flattened, said fixed cheek having a circular row of holes therein, a screwed spindle extending from the centre of the conical portion of said fixed cheek, a peripheral flange on said fixed cheek, adjacent its flat face, a circular guide of soft iron divided diametrically into two halves, said guide having its face adjacent the fixed cheek of the same shape as the adjacent face of the fixed

cheek, a peripheral rim on said guide, said peripheral rim being adapted to engage with the periphery of the fixed member and to co-operate with the said flange, a former fitted on said spindle, said former fitting against the flat apex of said fixed cheek, the former being adapted to receive a cylindrical portion of a diaphragm of the same shape as the adjacent faces of the fixed cheek and guide, said guide having a central hole therein through which the said cylindrical portion is adapted to pass, a removable cheek fitted on said spindle, said removable cheek having therein a recess of two different diameters, the portion of the recess of one diameter being adapted to receive one end of the said former, the other portion of said recess being adapted to receive the end of the cylindrical portion, a nut screwed on said spindle, said nut being adapted to force the removable cheek towards the fixed cheek whereby the former is clamped between the two cheeks, said guide having at least one notch therein for engagement by a wire for forming a coil on said cylindrical portion, a circular aluminium plate adjacent said fixed cheek, a circular row of soft iron pins in said aluminium plate, said pins fitting said holes with clearance, a tube to one end of which said aluminium plate is secured, a soft iron circular plate secured to the other end of said tube, a tubular permanent magnet between said aluminium plate and said soft iron plate and surrounding said tube, a circular casing surrounding said plates and said magnet, and screws passing through said plates and screwed into said fixed cheek.
